Primary Examiner — Kevin K Rudzinski*Assistant Examiner* — Richard Kearney(57) **CLAIM**

The ornamental design for a half-round ridge end cap, as shown and described.

DESCRIPTION

1. Half-round ridge end cap

1.1 : Perspective

1.2 : Top

1.3 : Right

1.4 : Left

1.5 : Bottom

1.6 : Front

1.7 : Back

A half-round ridge end cap intended for closing ridge tiles; it is adjusted for mounting with the ridge tile; by the use of the end cap one achieves aesthetic and functional protection of ridgepole end; the end cap is of half-round shape with circumferential annular embossment; it has mounting holes and wings to adjust the end cap to the ridge tile; all elements produce the individual character of the item.

1 Claim, 7 Drawing Sheets(56)
